By Owen C. Crompton,
His attorney.

UNITED STATES PATENT OFFICE.

CARL H. STROHL, OF FREMONT, OHIO, ASSIGNOR OF ONE-HALF TO HENRY C. RICE, OF FREMONT, OHIO.

TAPPET-VALVE SILENCER.

1,410,771.

Specification of Letters Patent. Patented Mar. 28, 1922.

Application filed July 19, 1920. Serial No. 397,201.

To all whom it may concern:

Be it known that I, CARL H. STROHL, a citizen of the United States, and resident of Fremont, in the county of Sandusky and 5 State of Ohio, have made an Invention App- pertaining to Tappet-Valve Silencers; and I do hereby declare that the following is a full, clear, and exact description of the invention, such as will enable others skilled 10 in the art to which it appertains to make and use the same, reference being had to the accompanying drawings, and to the characters of reference marked thereon, which form a part of this specification.

15 This invention relates to a silencer for tappet valves and particularly to those of the type used in connection with valve-in-the-head motors.

The object of the invention is the provision 20 of a silencing means of the character de- scribed which is simple and inexpensive in its construction, capable of being easily and quickly applied to a motor, and which is highly efficient in its operation.

25 The invention is fully described in the following specification, and while, in its broader aspect, it is capable of embodiment in numerous forms, a preferred embodiment thereof is illustrated in the accompanying 30 drawings, in which,—

Figure 1 is a top fragmentary view of a motor with a valve operating means thereof equipped with my silencer. Fig. 2 is a fragmentary side elevation thereof, and Fig. 3 is a perspective view of the silencer removed 35 from the engine.

Referring to the drawings, 1 designates the casing of an internal combustion motor, 2 a valve-stem projecting upward through 40 the head thereof, 3 a coiled compression spring for normally maintaining the valve seated and having one end thrust against the casing and its other end thrust against a shoulder or collar 4 on the stem, held in 45 position thereon by a pin 5. The customary cam operated tappet-rod 6 is disposed at a side of the casing, and valve opening move- ments are communicated from this rod to the valve stem through a tappet-lever 7, as well 50 understood in the art, such lever being ful- crumed intermediate its ends to a standard 8 rising from the casing.

The silencing means embodying the in- 55 vention is designated 9 and comprises a spring wire looped centrally upon itself in

the manner of a hairpin and having the looped end portion 10, the leg portions 11 extending normally at substantially a right angle therefrom, the terminal leg portions 12 extending normally at substantially right 60 angles from the leg portions 11 in the general direction of the looped portion 10 and connected to the leg portions 11 through coils 13, as best shown in Fig. 3.

In applying the silencer spring to a motor 65 it is placed in straddling relation to the valve-stem engaging arm of the tappet-lever 7 with its looped portion 10 engaged under the arm adjacent to the outer end thereof and with the legs of such looped portion, in 70 the present instance, extending cross-wise of the arm substantially to its top edge. The leg portions 11 then extend lengthwise of the upper end portion of the lever-arm to- 75 toward its fulcrum, with the coils 13 disposed at each side of the arm near its inner end. The leg portions 12 extend forward toward the valve stem and bear downward at their ends on the collar or shoulder 14, the spring 9 being placed under tension in this arrange- 80 ment by reason of the leg portions 11 and 12 being drawn from normal position toward each other, as shown. It is evident that the spring 9 exerts a continual pressure on the tappet-lever to prevent any rattling or clat- 85 tering thereof if its mounting becomes loose or if play occurs between the lever and either the tappet-rod or valve stem, or both.

It is preferable to position a pressure- 90 plate 14 over the shoulder or collar 4 to receive the thrust of the spring legs 12, such plate being of substantially U-form to adapt it to be placed in straddling relation with the valve stem 2 between the collar 4 and pin 5. The plate 14 is provided at opposite sides of 95 its slot 15 with perforations 16 with which the oppositely turned end portions 17 of the spring legs 12 are adapted to have hooked engagements.

It is found in practice that my invention 100 provides a simple and inexpensive means for effectively preventing the objectionable clat- tering of loose parts of tappet-valve oper- ating means of the valve-in-the-head type, and that the silencer springs may be easily 105 and quickly attached without dismantling any of the parts of the motor.

I wish it understood that my invention is not limited to any specific construction, ar- 110 rangement or form of the parts, as it is ca-

pable of numerous modifications and changes without departing from the spirit of the claims.

Having thus described my invention, what I claim as new, and desire to secure by Letters Patent, is,—

1. The combination with a motor tappet-lever and valve-stem, of a thrust member mounted on the stem, and a spring carried by the lever and having fingers in hooked engagement with the thrust member to retain it in engagement with the stem and to cooperate therewith to exert a tension between the thrust member and tappet-lever.
- 15 2. In a motor, the combination of a tappet-lever, a valve stem operated by movements of the lever, a spring acting on the stem to normally retain it in one position, a slotted thrust plate straddling the stem between the spring and tappet lever, and a silencer spring carried by the lever and having legs projecting outwardly therefrom in engagement with the thrust plate to retain it mounted on the stem and to exert a tension between the thrust plate and tappet lever.
- 20 3. A silencer means of the class described, comprising a spring wire looped on itself

with the legs thereof coiled intermediate their ends and with the outer portions angled with respect to the inner portions thereof and having laterally bent end terminals, and a thrust plate for mounting on a valve stem and having perforations for receiving the laterally bent end terminals of the 35 spring.

4. The combination with the tappet-lever and valve-stem of a valve-in-the-head motor, the valve stem having a spring thrust collar and a stop pin for the collar, of a silencer 40 spring looped on itself under the valve stem engaging arm of the tappet lever, with its legs extending inward a distance along opposite sides of the lever then coiled and having their outer end portions extending outward 45 toward the valve-stem and terminating in laterally extending end spurs, a thrust plate mounted on the valve-stem between its collar and stop pin and having perforations with which the end spurs of the silencer spring 50 engage, the silencer spring exerting a tension between the valve-stem collar and tappet lever.

In testimony whereof I have hereunto signed my name to this specification.

CARL H. STROHL.
